ATTORNEY

UNITED STATES PATENT OFFICE.

ORVILLE E. SHIRLEY, OF SALT LAKE CITY, UTAH.

EDUCATIONAL DEVICE.

Application filed February 10, 1923. Serial No. 618,245.

To all whom it may concern:

Be it known that I, ORVILLE E. SHIRLEY, a citizen of the United States, residing in Salt Lake City and State of Utah, have invented new and useful Improvements in Educational Devices, of which the following is a specification, reference being had to the accompanying drawings.

This invention is in the nature of an educational device although it may likewise be considered as a sort of game or toy; and the object is to provide an apparatus primarily calculated to improve the memory and perceptive powers.

15 In the drawing:

Figure 1 is a perspective view of the device with the shutter raised for exposing the characters on the rolls.

Figure 2 is a similar view with the shutter 20 dropped to cover the characters on the rolls.

Figure 3 is a longitudinal, vertical section.

In carrying out this invention a suitable box or case 1 is provided, having a window 2 in one end thereof and rollers 3 and 4 25 journaled transversely inside the box at each end, one of the rollers, as 3, being directly aligned with the window 2. The rollers 3 and 4 have each one end extended through the side of the box and cranks 5 and 6 are 30 attached at these ends for turning the rollers. The box is provided with a hinged lid 7, hinged at 8, and a shutter 9 depends from the free end of the lid and is adapted to close down inside the box between the roller 35 3 and the window 2. A strip of tape 10, of paper, cloth, or any suitably flexible material is attached at its two ends to the two rollers 3 and 4, and is wound upon these rollers. This strip of paper is covered with 40 numbers, words, pictures of objects of any kind, or characters of any kind or sort whatsoever, as may be desired, and it is obvious that as the rollers are turned by the cranks

5 or 6, the tape 10 will travel past the window 2, and the characters thereon will stand 45 revealed through the window to the sight of a person operating the apparatus. In the present drawing a series of letters *b-f-k-n-m* and figures *2-4-5-7-8* are shown 50 on the tape as revealed through the window, but it is understood that these letters and figures are merely illustrative of the purpose 55 of the device, and any other marks or characters or configurations may be employed.

In using this device the shutter 9 is raised 55 for a pre-determined space of time to enable the pupil or other person operating the device to obtain a sight of the characters revealed through the window 2; the shutter is then dropped, and the pupil undertakes to 60 recall the characters, objects, figures or words which he saw through the window. It is obvious that this sort of practice is strongly calculated to improve the powers of perception and memory.

65 While I have herein described a certain specific method of constructing and assembling the elements of my invention, it is understood same may be varied in minor details, not departing from the spirit of my 70 invention as defined in the appended claim.

I claim:

A device of the character described, comprising a box having a window in one end; two rollers transversely journaled in the box, one at each end; a configured tape on the rollers; a lid hinged to the open top side of the box; a shutter depending from the free end of the lid and adapted to close down into the box between the window and the adjacent roller; and means for rotating the rollers.

75 ORVILLE E. SHIRLEY.
